(57) **CLAIM**

The ornamental design for a shoe partially resembling a human foot, as shown and described.

DESCRIPTION

FIG. 1 is a perspective view of a shoe partially resembling a human foot showing my new design.

FIG. 2 is a right side elevation view of the shoe partially resembling a human foot.

FIG. 3 is a left side elevation view of the shoe partially resembling a human foot.

FIG. 4 is a top elevation view of the shoe partially resembling a human foot.

FIG. 5 is a bottom elevation view of the shoe partially resembling a human foot.

FIG. 6 is a front elevation view of the shoe partially resembling a human foot; and,

FIG. 7 is a rear elevation view of the shoe partially resembling a human foot.

The claimed ornamental design is shown in solid lines. Any dashed lines in the drawings represent environmental structure only and form no part of the claimed design.
